UNITED STATES PATENT OFFICE

97,892

DESIGN FOR A SMOKER'S PIPE

Ross R. Brady, Pontiac, Mich.

Application July 16, 1935, Serial No. 57,662

Term of patent 3½ years

To all whom it may concern:

Be it known that I, Ross R. Brady, a citizen of the United States, residing at Pontiac, in the county of Oakland and State of Michigan, have invented a new, original, and ornamental Design for a Smoker's Pipe, of which the following is a specification, reference being had to the accompanying drawing, forming a part thereof.

In the drawing:

Fig. 2 is a top plan view.

I claim:

The ornamental design for a smoker's pipe, as shown.

ROSS R. BRADY.
